UNITED STATES PATENT OFFICE.

JOHN M. EWEN, OF CHICAGO, ILLINOIS, ASSIGNOR TO THE LUXFER PRISM PATENTS COMPANY, OF SAME PLACE.

DESIGN FOR A PRISM-LIGHT.

SPECIFICATION forming part of Design No. 27,333, dated July 13, 1897.

Application filed June 15, 1897. Serial No. 640,930. Term of patent 14 years.

To all whom it may concern:

Be it known that I, JOHN M. EWEN, a citizen of the United States, residing at Chicago, in the county of Cook and State of Illinois, have 5 invented and produced a new and original Ornamental Design for Prism-Lights, of which the following is a specification.

My invention relates to a new design for prism-lights and is illustrated in the accompanying drawings, wherein—

Figure 1 is a perspective view, and Fig. 2 a section, through a prism-light containing my design.

Like parts are indicated by the same letter 15 in each figure.

A is the diamond-shaped body, and B B the prisms thereon.

I have shown certain angles of the prisms and certain angles of the body of the light; but the essential features of my invention are 20 found in a prism-light of a diamond shape with prisms across the same substantially parallel to its short axis.

I claim—

The design for a prism-light substantially 25 as shown and described.

JOHN M. EWEN.
